HOLDER FOR LIPSTICKS AND THE LIKE

Henri A. Lindsey, III, and Harry G. Long, Los Angeles, Calif., assignors to Allied Plastics Corporation, Los Angeles, Calif., a corporation of California

Application April 12, 1940, Serial No. 329,288

1 Claim. (Cl. 206—56)

This invention relates generally to holders for lipsticks, eyebrow pencils and similar soft pasty cosmetics, and particularly to cosmetic holders having the so-called swivel type of ejecting means for advancing the lipstick or other cosmetic beyond the end of the holder for use and withdrawing it into the holder afterwards.

The well known swivel type of ejecting mechanism involves a cosmetic carrier, a pair of concentric relatively rotatable cylindrical members outside the latter of which one has a straight, longitudinal slot or groove, while the other has a spiral slot or groove, and a means coacting with both of said slots or grooves and connected with the cosmetic carrier, so as to cause the latter to travel axially of the cylindrical members as one is rotated relatively to the other. A primary purpose of the present invention is to provide a swivel type of lipstick holder which is especially adapted to be made up of molded plastic materials. In the usual swivel holder, the cosmetic carrier, and the two relatively rotatable members having the straight and spiral slots or grooves, are not only concentric but are arranged to overlap one another. Such an arrangement is satisfactory for metal construction, wherein the wall thicknesses may be kept small, but in plastic construction the walls of the various members must be of such thickness that the holder becomes too great in diameter if the two relatively rotatable cylindrical members are placed outside the cosmetic carrier.

An object of the invention may therefore be stated to be to provide a swivel type lipstick holder of a construction capable of embodiment in plastic materials without becoming of inordinate diameter.

A further object of the invention is the provision of a lipstick holder characterized by extreme simplicity of construction, simplicity of assembly, and one which may be manufactured at very low cost.

A still further object of the invention is the provision of an improved and simplified swivel type holder of the type which is operated to eject the lipstick, and later to withdraw it, by rotation of the operating member in either direction, thus obviating the necessity of giving attention to the direction of rotation of the operating member.

The invention will be best understood from the following detailed description of selected present preferred embodiments thereof, reference for this purpose being directed to the accompanying drawings, in which:

Fig. 1 is an elevation of the holder;

Fig. 2 is a longitudinal section through the holder, the rotating propelling member being shown in elevation;

Fig. 3 is a view similar to Fig. 2 but with the cap removed, and with the propelling member rotated to a position in which the lipstick is

partly ejected, the propelling member being in this case shown in section;

Fig. 4 is a cross section taken on line 4—4 of Fig. 2;

Fig. 5 shows a stamping from which the cosmetic carrier is formed;

Fig. 6 is a detail showing a propelling member having a continuous cam groove;

Fig. 7 is a view similar to Fig. 2 but showing certain modifications; and

Fig. 8 is a detail of the plunger and follower members of the form of Fig. 7.

In Figs. 1 to 6 of the drawing, numeral 10 designates generally a casing, preferably and in this instance of cylindrical form fitted at its forward end with any suitable removable cap, such as the frictionally fitted cap 11 illustrated in Fig. 2. Casing 10 and cap 11 may be formed of any suitable material, such as metal, or molded plastic, though the present article is particularly designed for use of molded plastics, and that material is preferred because of its relatively low cost. Casing 10 has a cylindrical bore 12, which in the form here illustrated extends from end to end. Received within and slideable along bore 12 is the cosmetic carrier, which in the form of Figs. 1 to 6 consists of a cup 13, preferably formed of metal, as by a stamping operation, and within which is seated the lipstick or other cosmetic 14. Rotatably received within casing bore 12, to the rear of and in alignment with cup 13, is a propelling member 15 of cylindrical form, and formed preferably of plastic; this propelling member is preferably tubular in form (see Fig. 3) in order to reduce the material used. Member 15 is provided at its outer end with an enlarged operating knob or head 16 which abuts the rearward end of casing 10, and is formed, adjacent head 16, with an annular outwardly facing groove 17, which receives inwardly projecting locking lugs such as 18 formed inside the rearward end of casing 10 when members 10 and 15 are assembled. The lugs 18 are only slightly raised, and permit member 15 to be forced into working position, at which time they are received within groove 17 and hold the members thereafter against separation. Propelling member 15 is thus mounted for rotation within the rearward portion of casing 10, but is confined against axial movement with reference thereto.

The outer periphery of member 15 is formed with a cam slot or groove 20, and a follower means is provided engaging in said groove and operatively connected with cup 13, provisions also being made for confining cup 13 against relative rotation within casing 10. In the preferred and illustrative form instanced in Figs. 1 to 6, cam groove 20 is disposed in a plane at substantially 45° with reference to the axis of the

holder, and extends continuously around the outer periphery of the rotatable member 15. In order to reduce the material used, the inner or forward end 15a of member 15 is formed at a similar angle, the groove 20 being located relatively close to angular end 15a as illustrated. While cup 13 may be supported against rotation within casing 10 in various ways, it is preferable, and a feature of the present invention, that the follower element operatively connecting said cup with cam groove 20 serve also as a means for keying the cup against rotation; to this end, cup 13 is shown as provided with a rearward extension or leg 24 received wholly within and slideable freely along a longitudinal guideway or groove 25 formed inside casing 10, and provided at its extremity with an inwardly turned toe or projection 26 engaging within cam groove 20. Cup 13 may of course be fabricated in various ways, though it is preferably formed as a metal stamping. For instance, a blank such as 13a, see Fig. 6, may first be formed by a stamping operation, and it will be readily understood by those skilled in the art how this blank may then be rolled and bent by machine operation to form the cup 13 with its extended leg 24 and inwardly bent toe 26.

The operation of the device will now be apparent. Assuming the device to be in the position of Fig. 2, to eject the lipstick, the rotatable knob or head 16 is rotated relatively to casing 10. The direction of rotation is immaterial, rotation in either direction causing follower toe or projection 26 to follow the inclined cam groove 20, leg 24 sliding along guideway or groove 25 and advancing the cup 13 and lipstick fitted therein within casing 10, whereby the lipstick becomes ejected beyond the end of the latter. Continuous rotation of member 15 by means of head 16 causes follower element 26 to ride up groove 20 around one side of member 15 over the top of said groove and then down said groove around the other side of member 15 until the original position is again reached, the follower leg 24 and lipstick cup 13 being first advanced and then retracted during the complete revolution of head 16. It will thus be seen that a one-half turn of head 16 serves to move the lipstick from its completely retracted to its extreme advanced position, and that a further half turn brings the lipstick back to fully retracted position. Moreover, head 16 may be turned in either direction to accomplish ejection or retraction of the lipstick.

Attention is particularly directed to the fact that the propelling member 15 and article carrier 12 are both mounted within the casing 10, one in line with the other, rather than in the usual arrangement with the article carrier inside two relatively rotatable sleeve members, and to the fact that this arrangement permits the wall thicknesses to be adequate for plastic construction without the over-all diameter of the holder becoming undesirably great. Attention is further called to the exceptionally simple manner of assembly of the holder, which involves only insertion of the article carrier, and then insertion of the propelling member 15, the cam groove 20 being simply engaged with the follower toe 26 at the time the member 15 is inserted. And further, the operation of inserting the member 15

serves also to secure or lock the latter in its operative position. The entire article is made up of a relatively few simple parts, all of which with the exception of the metal cup are especially designed to be formed of plastic materials by conventional plastic molding procedures, and are especially designed to facilitate rapid assembly. The resulting article has a very low manufacturing cost, while at the same time its operation is smooth, convenient and efficient.

Figs. 7 and 8 show certain modifications, the device in this instance being in fundamental essence the same as that previously described, but being designed particularly for a nozzle type holder in which the pasty cosmetic is ejected in the form of a flat ribbon. In this instance the casing, designated at 10a, is formed with an integral nozzle type nose 30, having a usual flat aperture 31 through which the lipstick paste is exuded in a flat ribbon. The rotatable propelling device, designated by numeral 15a, is in this instance shown as provided with a double spiral thread forming double spiral cam grooves 34. The cosmetic carrier is in the form of a plunger 13a, formed on opposite sides with legs 24a, which are received in diametrically opposite longitudinal grooves 25a formed in casing 10a, said legs 24 having inwardly bent toes or projections 26a which engage in spiral grooves 34 on opposite sides of member 15a. Projections 26a are twisted, as indicated, so as to fill the grooves 34 in a direction longitudinally of the holder. The lipstick paste or other pasty cosmetic 14a is placed above plunger 13a as indicated. The spiral grooves 34 are of substantially lesser pitch than the cam groove 20 of the first described form of the invention, and that provision together with the use of the pair of diametrically opposite legs for the cosmetic carrier affords the additional pressure necessary with this type of holder to eject the cosmetic from the comparatively small aperture 31.

Certain present preferred illustrative embodiments of the invention have now been disclosed; it is to be understood, however, that these are for illustrative purposes only, and that various changes in design, structure and arrangement may be made without departing from the spirit and scope of the invention or of the appended claim.

We claim:

In a holder, the combination of a tubular casing having a longitudinal bore, an article carrier slidably mounted in one end portion of said bore and having sliding bearing against the inner surface of said bore, a cylindrical rotatable propelling member within the other end portion of said bore having rotational bearing against the inner surface of said bore and supported against longitudinal movement with reference to said bore, a cam groove having a lead longitudinally of the casing formed in the outer periphery of said propelling member, a longitudinal recess sunk in the inner surface of said bore, and a follower leg slidably received within said recess, so as to be outside said bore, said follower leg being connected at one end to the article carrier and having an inwardly turned toe at the other end engaging in said cam groove.
